UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

SEWING-MACHINE.

1,246,336.

Specification of Letters Patent.

Patented Nov. 13, 1917.

Application filed November 18, 1915. Serial No. 62,148.

To all whom it may concern:

Be it known that I, DUDLEY S. SEYMOUR, a citizen of the United States, residing at Oak Park, in the county of Cook, State of Illinois, have invented certain new and useful Improvements in Sewing-Machines, of which the following is a description, reference being had to the accompanying drawing, and to the figures of reference marked thereon.

The invention relates to new and useful improvements in sewing machines, and more particularly to a sewing machine wherein a trimming mechanism operates in advance of the stitching mechanism and devices cause cross threads to overlie and join the edges of the fabric on the upper face of the material.

An object of the invention is to provide an operating mechanism of the above character wherein the trimming mechanism and certain of the cross thread manipulating devices may be operated by the same actuating member on the main shaft, which actuating member is separate and independent from the actuating member for the needle or needles so that the load on the main shaft may be more evenly distributed.

A further object of the invention is to provide a mechanism of the above character wherein the cross thread manipulating devices include coöperating members, with an actuating member on the main shaft and devices operated thereby for vibrating the movable trimming member and one of the members of the cross thread manipulating devices, and a separate and independent actuating member on the main shaft and devices operated thereby for vibrating the needle bar and the other of the members of the cross thread manipulating devices.

These and other objects will in part be obvious and will in part be hereinafter more fully disclosed.

In the drawings, which show by way of illustration one embodiment of the invention:—

Figure 1 is a view in rear elevation showing a machine embodying my improvements; Fig. 2 is an end view of the same;

Fig. 3 is a view, partly in front elevation and partly in vertical section, of the machine;

Fig. 4 is an enlarged detail view from the rear of the machine showing a portion of

the overhanging arm, the vibrating arm of the trimming mechanism, the actuating rock shaft therefor, the rock arm for actuating the cross thread hooks, and actuating sleeve therefor;

Fig. 5 is an end view showing the end of the overhanging arm, a portion of the needle bar and the needles carried thereby, a portion of the presser bar, a presser foot supported thereon, the trimmer supporting yoke, and the operating arm for vibrating the trimmer and for oscillating the thread guides;

Fig. 6 is a view, partly in plan and partly in section, showing the end of the work support, the presser foot, the presser bar, the supporting yoke for the trimming blade, and the operating link for actuating the same;

Fig. 7 is a detail in vertical section, showing the presser bar, the presser foot supported thereby, the supporting yoke for the movable trimming member and the link for actuating the same;

Fig. 8 is a view, partly in plan and partly in section, similar to Fig. 6 but showing in addition thereto the thread hooks, the actuating link therefor, the thread guides, and the actuating link for the thread guides;

Fig. 9 is a detail, partly in section and partly in front elevation, showing the presser foot, the up-turned edges of the fabric, and the trimming blades.

The invention consists generally in a sewing machine having a work support and an overhanging arm which supports a needle bar carrying a needle or needles which reciprocates at the free end of the work support. Trimming blades are located in front of the needle or needles, and these trimming blades are disposed in a horizontal plane, and one of said blades is movable for trimming the up-turned edges of the fabric preparatory to abutting or slightly overlapping the same and joining the edges. Co-operating with the needles is a cross thread manipulating mechanism which lays cross threads across the meeting edges of the fabric, and this cross thread laying mechanism preferably includes a thread guide and a co-operating thread hook.

On the main shaft is an actuating eccentric which operates a train of devices connected with the needle bar for vibrating the same and connected with the thread hooks

for oscillating the thread hooks back and forth across the line of feed. There is a second independent eccentric on the main shaft and devices operated thereby for vibrating the movable trimming member and also for oscillating the thread guides back and forth in a direction substantially parallel to the line of feed.

It is well-known that the greater part of 10 the load on the operating shaft comes from the operating of the needles which are caused to penetrate the fabric and from the operating of the trimming blades which sever the fabric. By my mechanism as 15 above described, I am able to distribute this load more evenly on the main shaft and thus reduce to a minimum the vibrating strain on the machine.

Referring more in detail to the drawings, 20 I have shown my invention as applied to a sewing machine having a standard 1 carrying an overhanging arm 2 in the free end of which is mounted a needle bar 3 carrying, as herein shown, four needles 4. The needle bar 3 is vibrated by a needle lever 5 which is connected to the needle bar by a link 6. Mounted in the standard 1 is the main operating shaft 7 which is actuated by the usual belt wheel 8. Located on the main 30 shaft 7 is an eccentric with which an eccentric strap 9 coöperates, and this eccentric strap is connected at its upper end with the needle lever 5.

Extending outwardly from the standard 1 35 is an arm 10 which carries a horizontally projecting portion 11. At the free end of this horizontally projecting portion 11 is a vertically depending section 12 at the lower end of which is mounted a work supporting 40 arm proper 13. The arm 10 projects toward the operator, while the section 11 is substantially parallel with the overhanging arm. The work supporting arm 13, therefore, is located so that its free end is underneath 45 the free end of the overhanging arm 2, and the material to be stitched may be placed around said work supporting arm 13, the edges joined to form a tube, and the stitched tube fed off from the free end of the arm. 50 Said work supporting arm is provided with the usual feeding mechanism which is operated from a train of devices extending through the sections 10, 11 and 12, and this train of devices is actuated by the main shaft 55 7. As shown in the drawings, the four needles are arranged in two pairs, one in advance of the other, and a looper coöperates with each pair of needles. These loopers are located in the work supporting arm 13 60 and are likewise actuated by a train of mechanism operating from the main shaft 7.

The feed dog is indicated at 14 in Fig. 2 of the drawings. Coöperating with this feed dog is a presser foot 15 which is carried

by a presser bar 16 mounted in the overhanging arm, the trimming mechanism consisting of a fixed trimming blade 17 and a movable trimming blade 18. The fixed blade is connected to the presser foot.

The fabric sections to be trimmed, indicated at F in Fig. 9, have their up-turned edges f led through a guiding slot at the forward end of the presser foot and the movable trimming blade 18 coöperating with the fixed blade 17 trims these up-turned edges. 70 The trimmed-off strip may be deflected to one side of the needles by a strip deflector 19. The movable trimming blade 18 is mounted in an arm 20 which is clamped to a supporting yoke 21 (see Fig. 7). This supporting yoke is mounted on the presser bar 16 so as to turn freely thereon. Said yoke is forced downwardly relative to the bar 16 by a spring 22 which rests on the upper end of the yoke and engages a collar 23 which is fixed to the presser bar 16. The arm 20 is formed with a split collar 24 which engages a projecting sleeve 25 formed integral with the yoke, and this split collar is clamped to the sleeve by a clamping bolt 26. 80 A link 27 is pivoted at one end to a ball stud 28 fixed to the arm 20. The other end of this link 27 is freely connected to the lower end of an arm 29 which is fixed to the outer end of a shaft 30. 90

This shaft 30 is mounted in bearings 31 and 32 carried by the overhanging arm. The shaft 30 carries a second arm 33 which projects rearwardly therefrom, and this arm carries a ball stud 34 at its outer end with which an eccentric strap 35 is connected. The eccentric strap 35 coöperates with the eccentric on the main shaft 7 (see Fig. 3).

The cross thread manipulating devices, as herein shown, include thread guides 36, one 105 for each pair of needles, and thread hooks 37 which coöperate with the respective thread guides and the respective pairs of needles. The thread guides 36 are fixed to a swinging arm 38 which is mounted on a supporting 110 pivot bolt 39 carried by a suitable bracket attached to the overhanging arm (see Fig. 3). A link 40 is pivotally connected at one end to this arm 38, and at its other end said link is pivoted at 41 to the arm 29. As the 115 arm 29 oscillates, it will in turn oscillate the arm 38 carrying the thread guides so as to move the thread guides back and forth in a direction substantially parallel with the line of feed. 120

The thread hooks 37 are fixed to an arm 42, which is pivoted to swing about a vertical axis at 43. Fixed to the arm 42 is a second arm 44 which carries a ball stud on its outer end. A link 45 is connected at one 125 end to this ball stud, and the other end of this link is connected to a depending arm 46. The arm 46 is clamped to a sleeve 48 which

is mounted to oscillate freely on the shaft 30. Said sleeve is preferably made in two sections. Said sections are provided respectively with arms 49 and 50 which may be connected by a pin 51 or disconnected from each other at the will of the operator. The sections of the sleeve 48, when the machine is in action, are rigidly connected together. This sectional construction of the sleeve forms no part of my invention. The sleeve is also provided with a forwardly projecting arm 52 which carries a ball stud on its forward end. A link 53 at its lower end engages this ball stud and at its upper end said link is connected to a ball stud secured at 54 to the needle lever 5.

From the above description, it will be apparent that I have devised a construction wherein a single actuating eccentric on the main shaft 7 through the eccentric rod or strap 35, the shaft 30, the depending arm 29, and the links 27 and 40, respectively, vibrate the trimming blade and also the thread guiding hooks. I have likewise devised a construction wherein a single eccentric on the main shaft operating through the eccentric rod or strap 9 vibrates the needle lever, and this needle lever in turn reciprocates the needles and vibrates the thread laying fingers. The strain incident to the puncturing of the material by the needles is carried by one eccentric, while the strain incident to the severing of the fabric sections is carried by another eccentric. Not only are these heavy strains of the machine distributed on the two independent eccentrics, but all the other active mechanism above the work support is likewise actuated from these two eccentrics and distributed substantially equally on the two eccentrics, as the thread guides are vibrated from one eccentric and the thread hooks from the other.

It is obvious that minor changes in the details of construction and the arrangement of parts may be made without departing from the spirit of the invention as set forth in the appended claims.

Having thus described the invention, what is claimed as new is:—

1. A sewing machine including in combination, a standard, a main shaft located in said standard, an overhanging arm carried by the standard, a needle bar reciprocating in said arm, a trimming mechanism including trimming members operating on the fabric in advance of the needles, and an actuating member on the main shaft, and devices operated thereby for actuating the trimming member, a second actuating member on the main shaft, and devices operated thereby for actuating the needle bar, cross thread laying mechanism coöperating with the needles and including a thread guide and a thread hook, devices for actuating the

thread hook from one of said actuating members on the main shaft, and devices for vibrating the thread guide from the other actuating member on the main shaft.

2. A sewing machine including in combination, a standard, a main shaft located in said standard, an overhanging arm carried by said standard, a needle bar located at the free end of said overhanging arm, a plurality of needles carried thereby, a work supporting arm carried by said standard and having a free end extending underneath the free end of the overhanging arm, a trimming mechanism including trimming members operating on the fabric in advance of the needles, an actuating member on the main shaft, and devices operated thereby for actuating the trimming member, a second actuating member on the main shaft, and devices operated thereby for actuating the needle bar, cross thread laying mechanism coöperating with the needles above the work supporting arm and including a thread guide and a thread hook, devices for actuating the thread hook from the actuating member for vibrating the needle bar, and devices for vibrating the thread guide from the actuating member for the trimming members.

3. A sewing machine including in combination, a standard, an overhanging arm carried thereby, a needle bar mounted in the overhanging arm, needles carried by said needle bar, a main shaft located in the standard, a shaft mounted on the overhanging arm and extending lengthwise thereof, means for positively actuating said last-named shaft from the main shaft, a trimming mechanism including a horizontally movable trimming blade operating on the fabric in front of the needles, a depending arm carried by the shaft on the overhanging arm, and a link pivotally connecting said depending arm and the movable trimming blade.

4. A sewing machine including in combination, a standard, an overhanging arm carried thereby, a needle bar mounted in the overhanging arm, needles carried by said needle bar, a main shaft located in the standard, a shaft mounted on the overhanging arm and extending lengthwise thereof, means for positively actuating said last-named shaft from the main shaft, a trimming mechanism including a horizontally movable trimming blade operating on the fabric in front of the needles, a depending arm carried by the shaft on the overhanging arm, a link pivotally connecting said depending arm and the movable trimming blade, cross thread laying mechanism including a vibrating thread guide, and a link connected to said depending arm for vibrating said thread guide.

5. A sewing machine including in combination, a standard, an overhanging arm carried thereby, a work supporting arm having its free end extending underneath the overhanging arm, a needle bar mounted at the end of the overhanging arm, needles carried thereby, a presser foot, a presser bar supporting said presser foot, a trimming mechanism including a stationary member 10 mounted on the presser foot, and a movable trimming member coöperating therewith, a yoke mounted on the presser bar, an arm clamped to said yoke and carrying said movable trimming member, a shaft mounted

on the overhanging arm and extending 15 lengthwise thereof, a depending arm carried by said shaft, a link connecting said depending arm with the arm on the yoke supporting trimming member, and means for positively oscillating said shaft on the over- 20 hanging arm from the main shaft.

In testimony whereof, I affix my signature, in the presence of two witnesses.

DUDLEY S. SEYMOUR.
